UNITED STATES PATENT OFFICE

149,176

DESIGN FOR A TILTING TYPE CONCRETE MIXER

George A. Fleischmann, Milwaukee, Wis., assignor to Chain Belt Company, Milwaukee, Wis., a corporation of Wisconsin

Application July 12, 1946, Serial No. 131,528

Term of patent 14 years

(Cl. D14—3)

To all whom it may concern:

Be it known that I, George A. Fleischmann, a citizen of the United States, residing at Milwaukee, county of Milwaukee, State of Wisconsin, have invented a new, original, and ornamental Design for a Tilting Type Concrete Mixer, of which the following is a specification, reference being had to the accompanying drawings, forming part thereof.

In the said drawings:

Fig. 1 is a perspective view of a tilting type concrete mixer embodying my design with the mixing drum in position for charging and with the towing pole inserted and attached therethrough.

Fig. 2 is a perspective view from side and rear with the mixing drum in substantially the same position as it is in Fig. 1.

The dominant features of my design reside in the portions shown in full lines.

I claim:

The ornamental design for a tilting type concrete mixer, substantially as shown and described.

GEORGE A. FLEISCHMANN.
